(54) **SAW MILLS**

(76) Inventor: **Nathan Kirk**

*Nathan Kirk
Letters Patent*

The Schedule referred to in these Letters Patent (and making part of the same containing) a description in the words of the said (Nathan Kirk, himself of his improvement,) in

To all to whom these Presents shall come—

Be it known that I, Nathan Kirk of the County of Clinton and State of Indiana have invented a new and useful improvement in the construction and principle of common saw mills (and that the following is an exact description of the construction and operation of said machine as invented and improved by me.) The invention consists in the improvement of common saw-mills, so that by the mere operation of machinery, braces and scantlings, &c may be sawed to any given gauge without the assistance of human power, after the log has been slatted (and properly secured.) The process is to secure a log upon the carriage, having been slatted, start the mill by raising the flitter wheel gate, the log is sawn through; the same movement is used as the feed arm or hand shuts the flitter wheel gate, (and raises the gig wheel gate,)—the carriage is run back until the saw leaves the log, when by the operation of the machinery in the head block (and tail block) the log is moved the width of the plank intended. the log is again secured at the head block, the gig wheel gate is shut, the flitter wheel gate is raised and the saw commences cutting again, (and so on until the whole log is sawn up, when a foot on the carriage touches a lever which stops the whole mill.) The object is shown in the process or operation.

There are three principle operations of the improvement—viz:

1. the shifting of the log by means of machinery attached to the head block and tail block.
  - 2d. the working of the flitter wheel gate, and the gig wheel gate.
  - 3d. the moving the carriage backward (and forward) which two last are connected, with each other.
- 4th. The machinery in the head (and tail block) is substantially the same one therefore will only be attempted to be described. In the middle of the head block, (and on the*

form of a lever, the roller gage works. It has an oblique ground in the lower extremity, (and a key (a) attached to the upper extremity.) The ground by the motion of the carriage comes in contact with a permanent pivot, causing a lateral movement in the roller gage, which forces key (a) against the gage notches, in block (A) which having the log bar (or, b,) attached to it moves the log. On one side of the roller gage, there is a spring to keep key (a) firm in the notches, in the unid side of gage block (A). On the opposite side is a catch (c) which fastens in the gage notches, (while the mill is sawing) in opposition to key (a), just before the shifting of the log this latter key is withdrawn by passing over a permanent pivot, so as to let the notches pass, it is then restored to its place by a spring - 3 & 3. The two outer gates, are moved by machinery, attached to opposite ends of a lever, so that when one is opened the other is shut. The mill is put in motion by raising the flutter wheel gate. By the passage of the carriage the gate beam (d) is raised being attached by a chain or cord, to the beam carrier which corresponds to, (and is operated upon by the oblique angle at the side of the carriage. Before the log is sawed, through, the beam (d) is caught upon a notch, where it remains until the carriage rotates (and is ready to commence sawing, when a pivot on the carriage strikes a lever thrown off the notch, the beam comes down with such an impetus, as to raise the large gate (and to shut the gig wheel gate, when the mill commences sawing. The section exerted in the large gate is so great as to raise the small one, (and the large gate as before stated is raised by the impetus of the beam falling upon the opposition of the lever or the machinery attached thereto; Attached to the downward motion of the flutter wheel gate, is a lever having one end under the face hand, whereby it is thrown off the gig wheel to give the carriage liberty to run back.

The log is confined at the tail block with dogs in the usual manner. At the head block it is confined during sawing by the tail of a made fast to the log by plate nos. 282 - and for an

The log has a fastener to block (A), which being operated upon by the machinery in base block (B), moves the log. A similar ring may be

confines the log down during sawing, and just before the operation of shifting
in the log comes in contact with plate (7a) attached the guide, by which
its hold upon the log is loosened. As soon as sawing commences a spring
under the tumbling dog restores it to its place.
